UNITED STATES PATENT OFFICE.

ABRAHAM KULICK, OF NEW YORK, N. Y.

HAND BAG.

Application filed December 18, 1924. Serial No. 758,659.

To all whom it may concern:

Be it known that I, ABRAHAM KULICK, citizen of the United States of America, residing at the city, county, and State of New York, have invented new and useful Improvements in Hand Bags, of which the following is a specification.

My invention relates to improvements in the construction and particularly the arrangement of concealed pockets in hand bags.

The object of the invention is to provide certain new and useful improvements in hand bags of this character having concealed pockets for containing valuables which will not be accessible to unauthorized persons while the bag is being carried by the owner.

A further object of the invention is to provide a concealed pocket having a flap which folds upon itself and beneath the main cover of the bag to seal the mouth of the said pocket.

One embodiment of my invention is illustratively exemplified in the accompanying drawing, in which, Figure 1 is a perspective view of my improved bag showing the cover and bag in open positions; Figure 2 is a transverse sectional view of the bag showing the latter in closed position.

Referring to the drawing, 10 denotes the body of the bag having an integral cover portion 11 and interior section 12. The front, back and cover of the bag is cut from a single piece of material, as clearly illustrated in Figure 2. It will be understood of course that suitable linings will be provided for the bag, but for the sake of brevity such linings are not illustrated nor described. The interior back wall of the bag is provided with a pocket 13 which is constructed of a single strip of material 14, the latter being attached to the body 10, so as to provide a mouth 15 adjacent the fold of the main cover 11 and an upright mid-portion which forms the outside wall 16 of a concealed pocket 17. The backing 18 for the pocket 17 comprises a piece of material attached to the body 10 at the bottom thereof and disposed parallel and adjacent the wall 16. The upper end of the backing 18 projects substantially above the

wall 16 to form a flap 19 which folds along a line adjacent the upper edge of the front wall of the body 10. In order to seal the 55 pocket 17 the wall 16 thereof projects above the line of the flap fold so that when the latter is folded over on the face of the front wall the wall 16 and backing 18 cooperate to form a closure for the mouth of the said 60 concealed pocket. Both the cover 11 and flap 19 are provided with one member of a separable fastening means 20, the other members thereof being disposed on the front 65 wall of the body 10.

Having described my invention what I claim is:

1. A hand bag, having a body portion of one piece of material forming the front, back and cover portions, an internal partition comprising a pocket composed of adjacent strips of material stitched along their opposite edges to the body of the bag, one of said strips being longer than the other to form a flap to engage over the front of 70 the bag, both strips being folded to close the mouth of the pocket along a line short of the end of the shorter strip.

2. A hand bag, having a body portion of one piece of material forming a front and back, an internally arranged partition having a backing of one piece of material secured to the bottom fold of the body and having the free end adapted to fold over the front portion to close the pocket in 85 front of the partition, said partition further having a second strip of material attached at its inner end and disposed parallel to the first strip and having its upper free end projecting beyond the fold in the first strip, the said fold causing the two strips to be brought together when the free ends of latter are folded over the edge of the front portion.

3. A hand bag, having a body portion of a single piece of material folded to form front, back and cover portions, a second piece of material arranged within the body portion and having one end disposed parallel to and adjacent the back portion to form a pocket, the remaining portion of the second piece being attached to lower fold of the body portion then disposed in upright position and thereafter folded adjacent

the top of the bag, the free end beyond the latter fold forming a flap to fold over the front portion, and a third piece of material secured at its lower end to the bottom of the bag and having its upright portion adjacent the upright portion of the second piece to form a concealed pocket, the free

end of the third piece being adapted to fold with the first flap over the front wall of the bag. 10

In testimony whereof I affix my signature.

ABRAHAM KULICK.
